FLOATING SHOCKPROOF AND VIBRATION-LESS ASSEMBLY FOR DELICATE INSTRUMENT PANEL MOUNT

Edward J. Gallagher, Jr., 3501 Ednor Road,
Baltimore 18, Md.

Filed Mar. 2, 1961, Ser. No. 92,804
2 Claims. (Cl. 248—358)

The present invention relates to a shockproof or vibration proof mounting, and more particularly to such a mounting that is adapted to be used in conjunction with the support of delicate instruments or the like.

The primary object of the present invention is to provide a shockproof and vibrationless mount for delicate instruments or the like wherein such instruments can be safely supported or mounted whereby in the event of a vibration or shock, damage or shock to such delicate instruments will be minimized or prevented.

Another object is to provide a vibration dampener which can be used in conjunction with the support of various types of articles such as articles of furniture, work benches or the like, and wherein regardless of the direction of the vibration or shock, the present invention will compensate for such vibration or shock so as to prevent instruments or other articles that are being supported from being effected by such shocks or vibrations.

Still another object is to provide a shockproof and vibrationless assembly of the character described that may be used in conjunction with precision instruments, and further objects and advantages are to provide improved elements and arrangements thereof in a device of the character described that is economical to produce, durable in form, and conducive to the most economical use of materials and uniformity of members formed therefrom.

Still further objects and advantages will become apparent from the subsequent description in the specification.

In the drawings:

FIGURE 1 is a front elevational view of the shockproof and vibration absorber assembly of the present invention, and with parts broken away and in section.

FIGURE 2 is a sectional view taken on the line 2—2 of FIGURE 1.

FIGURE 3 is a sectional view taken on the line 3—3 of FIGURE 1.

FIGURE 4 is a sectional view taken on the line 4—4 of FIGURE 1.

FIGURE 5 is a sectional view taken on the line 5—5 of FIGURE 1.

FIGURE 6 is an enlarged sectional view taken on the line 6—6 of FIGURE 1.

FIGURE 7 is a view similar to FIGURE 6 but showing the parts in a different position.

FIGURE 8 is a view similar to FIGURES 6 and 7 but showing the parts in another or different position.

FIGURE 9 is a sectional view taken on the line 9—9 of FIGURE 6.

FIGURE 10 is an enlarged sectional view taken on the line 10—10 of FIGURE 1.

FIGURE 11 is a sectional view taken on the line 11—11 of FIGURE 10.

FIGURE 12 is an enlarged sectional view taken on the line 12—12 of FIGURE 1.

FIGURE 13 is a sectional view taken on the line 13—13 of FIGURE 1.

FIGURE 14 is a fragmentary sectional view illustrating a modification.

FIGURE 15 is a fragmentary sectional view of another modification.

2

FIGURE 16 is an elevational view illustrating a further modification.

FIGURE 17 is a sectional view taken on the line 17—17 of FIGURE 16.

5 FIGURE 18 is an elevational view generally similar to FIGURE 16 but showing a further modification.

Referring in detail to the drawings, the numeral 30 indicates the shockproof assembly of the present invention in its entirety, and it will be seen that the assembly 30 embodies an outer frame which is indicated generally by the numeral 37, FIGURE 1, and the outer frame 37 includes a pair of spaced parallel vertically disposed bars 31, and secured to the inner portions of the bars 31 are brackets 32, and the brackets 32 may be secured to the bars 31 in any suitable manner, as for example by means of bolts 33. First, second and third horizontally disposed spaced parallel crosspieces 34, 35 and 36 are arranged at right angles with respect to the bars 31, and these crosspieces are suitably secured to the brackets 32 as for example by means of bolts, rivets, welding or the like.

The numeral 38 indicates each of a first pair of similar mounting units that are connected to the first crosspiece 34, FIGURE 1, and as shown in FIGURE 12 due to the mounting units 38 embodies a base 39 which

25 includes a side wall portion 40 as well as a bottom portion 41, and the portion 41 has an opening 42 therein for a purpose to be later described. A disc 43 made of a suitable yieldable or resilient fiber like material is interposed between the portion 41 and the crosspiece 34, and

30 the numeral 44 indicates a support member that is adjustably connected to the base 39. The support member 44 includes a depending neck portion 45 which is provided with an annular groove or recess 46 therein, and as shown in the drawings a yieldable or resilient body piece

35 47 has a lip 48 that is seated in the recess 46. The numeral 49 indicates a coil spring which has one end engaging a recessed portion 50 within the neck 45, and as shown in the drawings there is provided a securing element or bolt 51 which includes a shank 52 that has

40 an enlarged head 53 on one end thereof, and an end portion of the shank 52 is threaded as at 54, there being a fastener or nut 55 arranged in threaded engagement with the threaded portion 54 in order to maintain the parts in their proper assembled position. The shank 52 is extended through an opening 56 in the support member 44.

45 As shown in the drawings a horizontally disposed block 57 is arranged above the crosspiece 34, and the block 57 is provided with a recess or cutout 58 therein. The

50 block 57 has a threaded opening 59 which registers with an opening 61 in an insert 62, and a bolt or securing element 60 has a portion thereof extending through the opening 61 and threadedly engaging the opening 59 so as to maintain the insert 62 connected to the block 57.

55 Electric cables 64 are clamped between arcuately recessed portions 63 in the insert 62 and block 57, and these cables 64 may include conductor wires 65 therein, FIGURE 13. The support members 44 are provided with annular grooves 66, and set screws or securing elements 67 are

60 adapted to extend through portions of the block 57 and engage the grooves 66, as for example as shown in FIGURE 13.

65 The upper portions of the support members 44 are snugly received in the recesses 68 in the block 57, and there is provided on the lower end of the support member 44 an enlarged circular shoulder 69 which is adapted to slide up and down in the base 39.

70 As shown in the drawings there is provided a generally rectangular open inner frame that is indicated generally by the numeral 70, and the inner frame 70 includes spaced parallel vertically disposed side members 71 as well as horizontally disposed spaced end mem-

bers 72, and the end members and side members are adapted to be secured together as at 73. Mounting units 38' are operatively connected to the lower end members 38 of the inner frame 70, and it will be seen that the mounting units 38' include a support member 44' that is slidably or adjustably connected to the base 39, and a yieldable or fiber washer or disc 74 is arranged contiguous to the support member 44'. The mounting unit 38' further includes a fiber disc 75 which is arranged contiguous to a washer 76, and a fastener 77 is arranged on a securing element such as a securing element 51 for maintaining the associated parts in their proper position.

The numeral 78 indicates a fixture or housing which is arranged within the inner frame 70, and the fixture 78 includes vertically disposed side sections 79 as well as horizontally disposed top and bottom sections 80 and 81. The numeral 82 indicates a door which may be provided for permitting a person to gain access to the delicate instruments within the fixture 78, and the door 82 may be opened by means of a handle 83, and the numeral 84 indicates a hinge for supporting the door 82.

Arranged around various spaced apart points relative to the fixture 78 are mounting devices which are indicated generally by the numeral 85, and these mounting devices 85 have a construction as later described in this application. There is also provided U-shaped yokes 86 which each include a web portion 87 that is secured in place as at 88, and each yoke 86 further includes a pair of spaced parallel arms 89, and the arms 89 are arranged so that the mounting devices 85 are supported between the arms 89 and adjacent portions of the fixture 78.

Attention is directed to FIGURES 6, 7 and 8 of the drawings, wherein there is shown in detail the construction of a mounting device 85 and it will be seen that the mounting device includes a spherical hollow body member 90 that is adapted to be made up of two generally semi-spherical sections 91 that are bonded or adhesively secured together as at 92, and the body member 90 is provided with an air aperture or opening 93 therein. Diametrically opposed generally arcuate saddles 94 and 95 engage outer portions of the body member 90, and there is provided diametrically opposed curved first and second base elements 96 and 97 which are arranged within the body member 90. The numeral 98 indicates a stem which has a threaded outer end portion 99, and a nut or fastener 100 is arranged in threaded engagement with the portion 99. The numeral 103 indicates a bushing that is slidably arranged on the stem 98, and the bushing 103 is provided with a rounded or arcuate surface 101. Bearing members 102 which may be made of a suitable material such as a fiber like substance are arranged in a suitable opening for the projection therethrough of the movable stem 98 so as to minimize friction between the parts. The stem 98 is provided with a circular shoulder 105 which engages an adjacent recess in the saddle 94. The inner end of the stem 98 is threaded as at 104 for threadedly engaging the base element 96.

There is further provided a movable plunger or piston 106 which is provided with a circular flange or shoulder 107 that engages a recess 108 in the base element 96, and an end portion 109 of the plunger 106 is arranged in threaded engagement with the base element 96. The piston 106 is arranged for sliding movement in a bore 110 of a cylinder 111, and the cylinder 111 is provided with an enlarged recessed portion 112 for receiving therein an end of the coil spring 113, and the coil spring 113 has the piston 106 slidably therein. Mounted within the base element 97 is an apertured fitting 114 that provides a seat for the valve member 115, and the valve member 115 is provided with a small aperture or opening 116 therein. A stem 117 has its inner end threadedly connected to the base element 97, and there is a circular flange or shoulder 118 on the stem 117, and as shown in FIGURE 7 for example the stem 117 is provided with a hollow interior or passageway 119 for the passage there-

through of air. The stem 117 otherwise has a construction which is somewhat similar to the construction of the stem 98.

Attention is now directed to FIGURE 14 of the drawings wherein there is illustrated a modification and wherein the numeral 120 indicates a portion of a member such as a work bench, leg of a table or the like, and the member 120 is provided with a recess 121 as well as a reduced diameter threaded aperture 122, and the numeral 38" indicates a mounting unit for the member 120. The mounting unit 38" includes a support member 44" as well as a securing element 51", and an end of the securing element 51" is adapted to engage the threaded opening 122 in the member 120. A support piece 123 is adapted to be connected to the support member 44", and the support piece 123 is adapted to engage a floor surface or the like.

Referring to FIGURE 15 of the drawings there is shown a further modification wherein the numeral 124 indicates a member such as an article of furniture, supporting table or the like, and the member 124 has provided in its lower end with a recess 125 which has communicating therewith a small opening 126, and the numeral 127 indicates a stud or pin which engages the opening 126, and a mounting device 85' is arranged as shown in FIGURE 15, and the mounting device 85' has connected to the lower portion thereof by means of a securing element 129 a support element 128, and an upwardly disposed member 130 is arranged adjacent the top portion of the mounting device 85'.

From the foregoing, it is apparent that there has been provided a shockproof mounting which is especially suitable for use with delicate instruments or the like, and in use with the parts arranged as shown in the drawings, it will be seen that the fixture 78 is arranged so that delicate instruments or the like supported therein will be protected from damage from vibrations, shocks or the like. The present invention is not restricted to any particular type of instrument and for example the fixture 78 may be hollow and access can be gained to the interior of the fixture 78 by manually gripping the knob 83 and opening the door 82 or swinging the door open about an axis extending through the hinge 84. The fixture 78 which has the instruments of a suitable nature or type supported therein is arranged within the inner frame 70, and the inner frame 70 is arranged within the outer frame 37, as shown in FIGURE 1.

There is provided around the fixture 78 a plurality of resilient mounting devices or mounting units which serve to function as shock absorbers so that in the event that vibrations or shocks occur, such shocks or vibrations will not be transmitted to the delicate instruments supported by the fixture 78 so that damage to such instruments will be minimized or prevented. It will be noted that the outer frame 37 may be rigidly affixed in place, but the inner frame 70 is resiliently supported within the outer frame 37, as for example due to the provision of the mounting units 38' and the upper mounting devices 85.

In addition, the fixture 78 is resiliently supported within the inner frame 70 by means of the mounting units 38' and the mounting devices 85 and this construction is such that in the event of a shock or vibration, such shocks or vibrations will be initially absorbed or damped by the lowermost mounting units 38' and by the uppermost mounting devices 85, and subsequently the shocks or vibrations will be damped or eliminated by the mounting devices 85 and mounting units 38' that are interposed between the fixture 78 and the inner frame 70.

As shown in FIGURE 1, there is provided the electric conductor wires or cables 64 which may be connected to a suitable source of electrical energy, and these cables 64 are clamped in place between the recesses 63 of the insert 62 and block 57, as for example as shown in FIGURE 13, and in addition there is provided for the block 57 the mounting units 38 which also help to dampen

any vibrations or shocks that may be transmitted along the cables 64.

As shown in FIGURES 6 through 8 for example, it will be seen that the mounting devices 85 are arranged or constructed so that regardless of the direction of the shock or vibration, the shock or vibrations will be damped or absorbed by the mounting device, and in addition each of the mounting devices are constructed so that a plurality of independent shock absorbing effects are provided which serve to effectively dampen or reduce the shocks before they are transmitted to the delicate instruments within the fixture 78. In FIGURE 6 a mounting device 85 is shown in normal position as for example when no shock or vibration is present, and in FIGURE 7 the position of the parts of the mounting device 85 is illustrated as for example when a shock or vibration occurs in a direction that is in alignment with the longitudinal axis of the piston 106. Thus, as shown in FIGURE 7 when such a vibration or shock occurs the body member 90 will become partially compressed, and since the body member 90 is made of a yieldable or resilient material such as a suitable rubber, plastic or the like, it will be seen that the shock or vibration will be partially absorbed due to the inherent resiliency of the body member 90. In addition it will be noted that when no vibration or shock is present, the valve member 115 is partially open so that air can flow through the hollow space or passageway 119 in the tubular member 117 and this air can also flow through the central aperture in the seat 114 and past the partially opened valve member 115. However, when the parts are in the position of FIGURE 7, the piston 106 will have moved from right to left through the bore 110 in the cylinder 111 and this will have the effect of closing the valve member 115 so that the only air that can flow between the bore 110 and the passageway 119 is that air which passes through the small aperture 116 in the valve member 115 and this restricted aperture or opening 116 thus acts as a further shock or vibration dampener since it will have a tendency to retard movement of the piston 106 in the bore 110. This is because the restricted opening 116 will only permit the air to flow therethrough at a certain rate or velocity which is less than the rate or velocity of the air as for example when the valve 115 is in the position of FIGURE 6, and the valve member 115 normally occupies or assumes the position such as that shown in FIGURE 6 due to the inherent resiliency of the valve member 115.

The spring 113 also helps dampen the vibrations or shocks, and for example it will be seen that as the parts move from a position shown in FIGURE 6 to a position such as that shown in FIGURE 7, the coil spring 113 will be compressed between the portion 112 of the cylinder 111 and the portion 108 of the base element 96, and this spring 113 will thus serve to take up some of the shock or absorb the vibrations so that it will be seen that each of the mounting devices 85 includes a plurality of different means for helping to reduce or eliminate shocks that would otherwise be transmitted through the supporting structure to the delicate instruments that may be arranged in the fixture 78. After the shocks or vibrations have disappeared or been absorbed, the parts will return from a position such as that shown in FIGURE 7 to a position such as that shown in FIGURE 6 due to the inherent resiliency of the parts such as the inherent resiliency of the body member 90 and the coil spring 113.

In addition the mounting devices 85 are constructed so that shocks or vibrations will be absorbed or damped even when they are not directed along a straight line as shown in FIGURE 7, and in this connection attention is directed to FIGURE 8 wherein there is illustrated the action which takes place when a shock or vibration occurs that is not along the longitudinal axis of a member such as the stem 98. It will be seen that when such a vibra-

tion or shock occurs, the body member 90 can be partially compressed and the rubber like or resilient construction of the body member 90 will function to help absorb such shocks or vibrations, and also the coil spring 113 will be partially compressed to also help absorb the shocks or vibrations and in addition, the valve member 115 will move from the position shown in FIGURE 6 to the closed position of FIGURE 8 so that the only air traveling between the bore 110 and the passageway 119 must pass through the restricted aperture 116 and this restricted aperture helps dampen or retard sliding movement of the piston 106 in the bore 110 so as to also aid in the shock absorbing effect that is desired. Furthermore, it will be noted that the stems or members 98 and 117 are capable of pivotal movement within the bearings 102 and thus regardless of the direction of the shock or vibration, the parts can automatically adjust in order to absorb the shocks. The fitting or bushings 103 are slidable on the members 98 and 117 and these elements 103 have the rounded surfaces 101 which are adapted to engage the adjacent bearings 102 in order to help orient the parts and permit the pivotal movement to take place in order to help prevent the shocks from being transmitted to the delicate instruments being supported. The nuts or fasteners 100 are threaded on the portion such as the portions 99 of the stems so that these nuts 100 function as limit stop members in order to insure that the parts will be maintained in their proper assembled relation and also these stop members 100 define abutments whereby the elements 103 can slide on the stems 98 and 117 so that for example the parts can move back and forth between the positions such as that shown in FIGURE 6 and that shown in FIGURE 8.

The body members 90 are each provided with an aperture or opening 93 so that air can flow through this aperture 93, as for example when the body member 90 is expanding or contracting during movement of the parts from a position such as that shown in FIGURE 6 to a position such as that shown in FIGURES 7 or 8.

As shown in FIGURE 1, the mounting devices 85 at the opposite sides of the fixture 78 are fastened between the sides 79 of the fixture 78 and the side portions 71 of the inner frame 70. In addition a pair of the mounting devices 85 are interposed and fastened between the top 80 of the fixture 78 and the top portion 72 of the inner frame 70, and also a pair of mounting devices 85 are arranged or interposed between the crosspiece 36 and the top member 72 of the inner frame 70. Other mounting devices 85 are affixed to the arms 89 of the yoke 85 and as shown in the drawings such as in FIGURE 2 for example the mounting devices 85 engage opposite surfaces of the fixture 78 and this arrangement is such that regardless of the direction of the shock or vibration, the mounting devices will be able to absorb or dampen the same so as to insure that the delicate instruments in the fixture 78 will not be damaged. The mounting devices 85 all have generally the same construction and operation although as previously stated they are adapted to be fastened to and used with different parts of the apparatus but in general the function of the various mounting devices is similar.

The outer frame 37 has a generally rigid construction, that is the bars 31 and crosspieces 34, 35 and 36 are rigidly secured together as for example by means of the elements 32, so that in effect the outer frame will have a tendency to transmit the shocks or vibrations therewithout any substantial or appreciable amount of dampening taking place. However, the shocks or vibrations will not ordinarily reach the inwardly disposed fixture 78 since in order to reach the fixture 78 such shocks or vibrations will have to move through the mounting devices and mounting units and since these mounting devices and mounting units are constructed so that they act as shock absorbers, it will be seen that the delicate

instruments in such a fixture will be safely supported and protected.

The present invention also includes the mounting units 38 which help insure that no shocks or vibrations will be transmitted along the conductor 64 to the fixture 78, and the conductors 64 are adapted to be used for connecting various types of electronic instruments or the like in the fixture 78 to a suitable source of electrical energy. Thus, any shocks which may have a tendency to travel along the conductors 64 will be absorbed in the mounting units or shock absorbers 38 which have a construction such as that shown in FIGURE 12 and it will be seen that for example when such a shock or vibration occurs, the support member 44 can move inwardly into the base 39 to compress the element 47 and also compress the coil spring 49, and since the element 47 is made of a suitable material such as rubber, plastic or the like, the element 47 will act as a shock absorber, and also the coil spring 49 will act as a shock absorber so that such shocks will not be transmitted along the conductors 64 to the fixture 78. After the shocks have been dissipated or absorbed, the inherent resiliency of the element 47 on the coil spring 49 serves to return the parts to their normal positions such as that shown in FIGURE 12.

The mounting units 38' have a construction and operation generally similar to the mounting units 38, however, the mounting units 38' have a modified or different type of support member 44', and as shown in FIGURE 10 a fiber washer 74 is adapted to be interposed between the support member 44' and the adjacent element 81, and this fiber washer 74 may move or shift slightly along the element 81 so as to permit the parts to automatically adjust to a position that helps minimize breakage or damage thereto.

While the present invention has been specifically described for use in connection with the support of delicate instruments or the like, it is to be understood that the mounting of the present invention is not restricted to use with apparatus or structure for supporting such delicate instruments since the present invention can be used in any type of structure where it is desirable to provide a vibrationless or shockproof mounting. Thus, instead of supporting delicate instruments in the fixture 78, other types of articles can be supported or arranged therein as desired or required. Also, as shown in FIGURE 14 the mounting unit 38' can be used in the lower end of a support or the like as indicated by the numeral 120, and the support 120 may be a leg of a table, work bench or the like, and a plurality of the mounting units 38'' of FIGURE 14 can be used, one for each leg of the work bench or table or the like. Thus, articles of a delicate nature can be supported on such a work bench in such a manner that shocks or vibrations will not be transmitted to the tools or other articles which are being supported. In FIGURE 14 the mounting unit 38' is shown to include the support piece 123 which is adapted to engage the floor or the like, and this support piece 123 is suitably secured to the support member 44', and the support member 44' is adjustably or telescopically connected to the base 39. The device of FIGURE 14 is shown to comprise the coil spring 49 as well as a securing element 51" and there is also provided the yieldable body piece 47. The securing element 51" serves to maintain the parts properly assembled together, and it will be seen that in the event of a shock or vibration, the support member 44" can move inwardly into the base 39 so as to compress the coil spring 49 and flex the yieldable body piece 47 so that in effect the body piece 47 and coil spring 49 will function as shock absorbers to dampen the shock or vibration which would otherwise be transmitted through the member 120 to the articles being supported. The securing element 51" can be adjusted as for example by arranging a screw driver or

other tool in engagement with the kerf in the head of the securing element 51" so that the tension exerted by the spring 49 can be varied or regulated as desired. The support piece 123 may be made so that it can be disconnected or removed from the support member 44" if desired or required.

In the modification of FIGURE 15 one of the mounting devices is shown in an application that is somewhat similar to the arrangement of FIGURE 14, and it will be seen that in FIGURE 15 the numeral 85' indicates a mounting device which engages a recess 125 in the lower portion of the leg or other support 124 which may be part of a work bench or the like that is used for supporting delicate instruments, tools or other articles where such articles are desired to be protected against shocks, vibrations and the like. The support element 128 is adapted to be secured to the lower end portion of the mounting device 85' as for example by means of the securing element 129, and the securing element 129 may be provided with a passageway similar to the passageway 119 so as to permit air to pass therethrough as the resilient body member of the mounting device 85' expands or contracts due to vibrations or shocks being damped thereby. The member 130 is adapted to be arranged adjacent the upper end of the mounting device 85', and the stud 127 is adapted to engage a suitable opening 126 in the lower portion of the member 124 so that the mounting device 85' will be maintained in its proper location.

The parts can be made of any suitable material and in different shapes or sizes.

Also, a unit such as that shown in FIGURE 14 or such as that shown in FIGURE 15 can be used on the lower end of a table or chair leg, and the mounting mechanisms can be used in other applications such as in conjunction with doors or windows where it is desired to dampen shocks or vibrations. Suitable washers, bearings, braces or the like can be used wherever desired or required. The bearing members such as the members 102 may be made of a suitable fiber like material so as to minimize friction and wear between the various moving parts. The parts including the elements 102 and 103 and 98 constitute a swivel ball type of socket which permits the necessary movement to take place as the shocks or vibrations occur. The yieldable body piece 47 is adapted to have its lip 48 snugly seated in the recess 46 so as to provide a snap in type of construction which permits the body piece 47 to be firmly held in place, and also this construction permits a member such as the member 47 to be maintained in its proper aligned position. The sections such as the sections 91 of the body member 90 may be secured together as at 92 by means of vulcanization. The members such as the members shown in FIGURES 14 and 15 can be used at the lower ends of legs of furniture such as tubular chairs, desks or the like. In addition, the present invention functions as a leveler and stabilizer when used as shown in the drawings.

A construction such as that shown in FIGURE 1 is especially suitable for supporting delicate instruments as for example in the vicinity of missile firing ranges, as for example when it is necessary to protect such delicate instruments from shock or vibrations that frequently occur as a result of a rocket, missiles or the like being discharged. In addition, the present invention is especially suitable for use in aircraft where it is necessary to support various types of instruments in such a manner that they will not be subjected to the damaging effects of various types of shocks or vibrations. The present invention is constructed so that shocks or vibrations from all directions will be damped, and the present invention can be used in conjunction with various articles of furniture, hospital equipment, office equipment, machinery, delicate instruments or the like.

The parts can be made large or small depending upon the size of load being supported, and the present invention will also function to help prevent sound waves from being transmitted to instruments or the like. Certain parts of the mounting units or devices may be made of a material which also prevents the transmission of electricity therethrough, and for example the fiber washers can also function as electric insulating members so as to prevent static electricity or the like from entering or damaging or otherwise interfering with various types of delicate instruments. The members such as the saddles and base elements which are contiguous to the spherical body member 90 are shaped arcuately or curved and have rounded surfaces thereon so as to insure that there will be no sharp edges to puncture or otherwise damage the body member.

Referring now to FIGURES 16 and 17 of the drawings, the numeral 78' indicates a fixture or box like member which can be used for any desired purpose, as for example delicate instruments or the like can be supported in or on a fixture such as the fixture 78'. The mounting devices 85 may be arranged as shown in FIGURE 16, and the numeral 135 indicates a horizontally disposed frame that is arranged above a surface such as the floor surface 136, and the mounting devices 85 can be used for preventing damage or harm to instruments being supported by the fixture 78'.

In the modification of FIGURE 18, the box 78' or fixture 78' can be again used for supporting various types of instruments or the like, and mounting units 38 can be arranged on opposite sides of the frame 135 so as to help provide a vibrationless mounting or support for the unit or member 78'.

As shown in FIGURE 12 the resilient body piece or grommet 47 has a lip or flange 48 that is snugly engaged in the recess 46, and a similar construction is adapted to be used in all of the other such mounting units, and this is an important feature or aspect of the present invention and for example represents an improvement over the construction of the levelers shown in my co-pending patent application Serial No. 781,041, filed December 17, 1958, now Patent No. 3,027,680. Thus, this construction is such that the grommet or element 47 will move in unison with the member 44, and the support members may be provided with cut away or recessed portions 137 that reduce the bearing surface between the support members and their coacting bases so that the necessary or desired sliding or reciprocating action can take place in the most advantageous and efficient manner.

It is to be understood that the present invention can be used in various different applications or uses so that the same is not restricted to use in connection with the supporting of delicate instruments or the like.

With further reference to the construction such as that shown in FIGURES 6, 7 and 8, and in particular as shown in FIGURE 8, it will be seen that this construction provides a stiffener on one side of the mounting device so as to insure that the device will move properly to an inclined position and give equal pressure at all times during its travel and yet permit air to escape and enter as required for the load action as the load action increases or decreases.

As stated previously an important aspect of the present invention is the resilient grommet 47 which has the lip 48 that engages the groove or recess 46 so that the support member and grommet will move or function as a single unit, and this is an improvement over a construction such as that shown in my prior patent No. 3,027,680.

Although the invention has been herein shown and described in what is conceived to be the most practical and preferred embodiment, it is recognized that the departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A device of the character described comprising an outer frame embodying vertically disposed spaced parallel bars, a pair of horizontally disposed crosspieces secured in vertically spaced relation to said bars, a first pair of similar mounting units connected to the lower of said pair of crosspieces, each of said mounting units comprising a base including a bottom portion provided with an opening therein, and said base further including a cylindrical side wall portion, a yieldable disc interposed between said base and said lower crosspiece, a support member adjustably connected to said base and said support member including a side section having a circular shoulder slidably engaging the inner surface of the side wall portion of the base, a neck depending from said support member and said neck having an outer annular recess therein, a yieldable body piece having a lip on its upper end engaging said recess, a securing element extending through said support member and through said base and through said lower crosspiece and said securing element having a fastener on its lower end, said securing element further including a shank having an enlarged head on its upper end, a coil spring circumscribed on said shank and said coil spring being arranged within said yieldable body piece, an inner frame interposed between said bars and between said cross pieces, said inner frame comprising spaced parallel vertically disposed side members and spaced parallel horizontally disposed end members, said lower end member connected to said support members of said mounting units, resilient mounting devices interposed between the other end member and the other crosspiece and between the side members and bars, a fixture arranged centrally within said inner frame, mounting units interposed between the lower end member of said inner frame and the bottom of said fixture, mounting devices interposed between the sides of said fixture and the side members of the inner frame, U-shaped yokes including webs secured to the end members of the inner frame and spaced apart arms the ends of which overlap in spaced relation the front and back respectively of the end portions of said fixture and resilient mounting devices interposed between the end portions of said arms and fixture.
2. The structure as defined in claim 1 wherein each of said mounting devices comprises a resilient spherical hollow body member having an aperture therein, diametrically opposed arcuate saddles arranged adjacent the outer portions of said body member, diametrically opposed curved first and second base elements arranged within said body member, a stem engaging one of said base elements and adjacent saddle, and said stem having a bushing slidably arranged thereon, a fastener connected to said stem, coacting bearing pieces having said stem adjustably connected thereto, a piston slidably arranged in said body member, a coil spring connected to said piston, a cylinder having a bore for slidably receiving said piston, an apertured fitting having a valve member arranged contiguous thereto, a stem connected to the second base element and said stem having a passageway therein, a fastener on said last named stem, and a bushing slidable on said last named stem.
